Everett M. Cutts

UNITED STATES PATENT OFFICE.

FREDERICK C. HARRIMAN, OF ARDSLEY-ON-HUDSON, IRVINGTON, NEW YORK.

STRAP-FASTENER.

1,229,263.

Specification of Letters Patent. Patented June 12, 1917.

Application filed May 8, 1916. Serial No. 95,995.

To all whom it may concern:

Be it known that I, FREDERICK C. HARRIMAN, a citizen of the United States, residing at Ardsley-on-Hudson, in Irvington, in the 5 county of Westchester and State of New York, have invented new and useful Improvements in Strap-Fasteners, of which the following is a specification.

My invention relates to strap fasteners, 10 and its objects are to afford a simple means for securing together the ends of a band around articles of various sizes, to dispense with prongs, sharp buckle tongues, and holes therefor, to utilize the tightness of 15 the band as a means for insuring the binding of the fastener and to simplify and render more effective the construction and operation of the several parts.

I am aware that there are now in common 20 use many devices designed for binding or securing various papers, documents, boxes and other articles of almost every nature and description. I am also aware that belts employing buckles of various 25 construction are also in common use. I have found, however, from observation and experiment that such forms of binding devices are in large part objectionable, because of their employing as a part of the 30 securing device features which of necessity tend to tear, cut or in other ways to destroy or diminish the tensile strength of the belt or band to which they are applied.

With my improved strap fastener, however, 35 I have been able to overcome the defects and objections above set forth. There being no prongs or claws employed as a part of the securing means, I have eliminated what has heretofore been a common 40 cause of objection. With the simplification of the construction of my metallic plate, I am thereby enabled to use less metal, while, at the same time, not detracting in the least from its value as a securing device. Through 45 the use of the undulating tongue I am enabled to secure a much firmer grip upon the end of the band than heretofore, the undulation thereof serving to press down and embed itself in the fabric and firmly to 50 hold the end of the band in the desired position.

Attention is hereby directed to the drawing, in which similar numerals of designa-

tion refer to similar parts throughout the several views:

55

Figure 1 is a view in perspective showing the application of my improved strap fastener to a bundle of ordinary size;

Fig. 2 is a plan view of my rectangular securing strip of resilient metal showing 60 one end of the strap affixed thereto; and

Fig. 3 is a longitudinal section of the securing device shown in Fig. 1, taken through the metal strip and parts adjacent thereto.

65

Referring to the drawing:

The strip 4 is stamped from a large metallic sheet in the manner which is well known in the art for stamping out any article of similar character. Preferably, the 70 said sheet is of such thickness as to admit of considerable resiliency in the strip, after the same has been stamped therefrom.

As will be observed in Fig. 2, the said strip 4 is preferably rectangular in shape 75 and has near one end thereof the tongue 5 which is integral therewith and extends laterally thereto, and has the portion 6 concave in shape, and the portion 7 convex, thereby rendering the said tongue undulating in character. Out of said strip, in proximity to said tongue, is cut a large rectangular slot forming on each side of said tongue the openings 8 and 9, the latter of which is made considerably wider than 80 the former, for the purpose which will be hereinafter described. At the other end of the said rectangular strip is the slot 10 similar in shape to the opening 9 and having affixed thereto the end 11 of the strip 90 12. All of the said slots are of such length as readily to admit the full width of the strip 11.

To secure my improved strap fastener to a parcel or other object, the said device is 95 placed generally in the position shown in Fig. 1. The free end 13 is then passed downwardly through the opening 9, whence it passes underneath the tongue 5 and the main portion of the strip 4, emerging 100 through the opening 10 which as well as the opening 9, is of sufficient width to admit of the ready insertion of both ends of the strip 12. The end 13 is then carried backwardly toward the tongue 5 and is inserted beneath the same, when it will occupy 105

the position shown in Fig. 3. It will accordingly be observed that the tongue 5 presses down upon two layers of the strip 12 and is embedded therein, and serves to bind the said layers firmly against the portion 14 adjacent to the opening 9.

As will be observed, any tension upon the ends of the strip 13 or, in fact, upon any portion of the strip 12, serves to bind the ends of said strip only the more firmly in position, and thereby to utilize the tightness of the band to effect a locking of the parts and prevent dislodgment of the securing strip 4.

15 What I claim and desire to secure by Letters Patent is:

1. In a strap fastener, a buckle consisting of a flat metallic plate, one end of which has a wide elongated slot in which 20 dips an undulated ribbonlike tongue ex-

tending laterally to said plate, and the other end of which has a narrow elongated slot extending in the same direction as the other slot.

2. In a strap fastener, a buckle consisting 25 of a flat metallic plate, from one end of which is cut an undulated tongue dipping into a wide elongated slot, said tongue being located nearer the inner than the outer edge of said slot, and the other end of which 30 plate has a narrow elongated slot extending in the same direction as the other slot.

In testimony whereof I have hereunto set my hand, in presence of two subscribing witnesses, this 4th day of May, 1916.

FREDERICK C. HARRIMAN.

Witnesses:

THEO. KEELER, Jr.,
H. C. SLATER.
